FACE MASK FOR HOUSEHOLD USE OR THE LIKE

Roberta E. Williams, P.O. Box 2410, New Orleans, La.

Filed Feb. 8, 1963, Ser. No. 73,489

Term of patent 3½ years

(Cl. D83—1)

Fig. 1.

Fig. 2.

Fig. 3.

FIG. 1 is a front elevation of a face mask for household use or the like showing my new design;

FIG. 2 is a side elevation thereof; and

FIG. 3 is a rear elevation thereof.

The outer and inner edges of the mask are stippled to show contrast.

The broken lines on the drawing are for illustrative purposes only.

I claim:

The ornamental design for a face mask for household use or the like, substantially as shown and described.
